(57) **CLAIM**

The ornamental design for an electronic device, as shown in the accompanying drawings and described above.

DESCRIPTION

FIG. 1 is a top front perspective view of an electronic device in accordance with the present invention.

FIG. 2 is a top rear perspective view of the electronic device of FIG. 1.

FIG. 3 is another top front perspective view of the electronic device of FIG. 1.

FIG. 4 is a bottom front perspective view of the electronic device of FIG. 1.

FIG. 5 is a bottom rear perspective view of the electronic device of FIG. 1.

FIG. 6 is a top plan view of the electronic device of FIG. 1.

FIG. 7 is a bottom plan view of the electronic device of FIG. 1.

FIG. 8 is a front elevation view of the electronic device of FIG. 1.

FIG. 9 is a rear elevation view of the electronic device of FIG. 1.

FIG. 10 is right elevation view of the electronic device of FIG. 1; and,

FIG. 11 is left elevation view of the electronic device of FIG. 1.

The broken lines shown herein are for illustrative purposes and form no part of the claimed design.
